CONTROL SYSTEM

Benjamin W. Jones, Schenectady, N. Y., assignor
to General Electric Company, a corporation of
New York

Application November 30, 1939, Serial No. 306,933

13 Claims. (Cl. 172—179)

My invention relates to control systems, more particularly to systems for controlling the starting, stopping and running of electric motors, and has for an object the provision of a simple, reliable, inexpensive and improved system of this character.

More specifically, my invention relates to systems for controlling the acceleration of an electric motor as a function of time. In addition, my invention relates to systems for controlling the counter current braking or "plugging" of an electric motor as well as the acceleration in the reverse direction after the motor has been slowed down by "plugging" to a predetermined low speed, preferably substantially to zero speed or standstill.

Another object of my invention is the provision of electromagnetic means, preferably including a plurality of multilegged frames each having a pair of energizing windings, for controlling the connection of suitable current limiting means, such as a plurality of resistors, with the motor circuit controlled and for controlling the disconnection of said current limiting means from said motor circuit.

A further object of my invention is the provision of means for controlling the energization of the windings of at least one of the electromagnetic devices so as to render the current limiting resistance used for "plugging" inactive during normal starting and normal running operation of the motor substantially without time delay, while controlling the energization of these windings during the counter current braking or "plugging" operation of the motor so as to prevent the electromagnetic device from rendering the "plugging" resistor inactive, until the speed of the motor is sufficiently reduced for safe operation in the opposite direction, preferably this speed being substantially standstill.

A still further object of my invention is the provision of means for controlling the energization of the windings of the electromagnetic devices which control that portion of the current limiting means used for acceleration, such as a plurality of accelerating resistors, in a manner whereby each electromagnetic device is operated to render inactive the accelerating resistor controlled by it, only after a predetermined time interval has elapsed from the instant a preceding one of the resistors was rendered inactive.

In carrying my invention into effect, I preferably employ an electromagnetic time interval device of the type disclosed and broadly claimed in the U. S. patent application of Fred H. Winter, Serial No. 187,753, filed Jan. 29, 1938. The Winter time delay device comprises a multi-legged magnetic structure having two energizing windings thereon and an armature carrying a switch contact, the armature being biased to a prede-

termined position. In the predetermined position, or what is termed the "normal unattracted" position, the armature is arranged to be magnetically restrained in this normal position when a certain one or both of the energizing windings are energized. The armature is moved to the attracted position from its normal position only when a certain one of the windings is energized and the other winding de-energized or when the windings are both energized in a direction to complement each other. Generally speaking, when both windings are energized in a manner to magnetically restrain the armature in its unattracted position, one of the windings may be short-circuited and then the other winding will cause a reversal of flux in a portion of the frame against the time delay effects of the other winding to effect time delayed operation of the armature to its attracted position. This type of time delay operation and certain modified forms of it are used in the sequential time delay control of the accelerating resistors to accelerate the motor.

A similar type of electromagnetic structure provided with an armature is used in the preferred embodiments of my invention to control the "plugging" resistor. However, in this case one of the windings is connected to be energized responsive to a suitable electrical condition of the motor circuit, such as the countervoltage of the motor. Under normal operating conditions of the motor, the last mentioned winding is energized in a direction to complement the magnetic forces generated by the other winding, thereby to operate the armature to its attracted position promptly without any substantial time delay. In this manner, if the motor is started from rest or is running in the proper forward direction, the "plugging" resistor is promptly rendered inactive by short-circuiting and the control of the circuit is transferred entirely to the accelerating resistors. If, however, the motor is "plugged," the countervoltage effect on one or both of the windings is such that the magnetic forces in the electromagnetic structure magnetically restrain the armature from operation to the attracted position until the motor speed drops substantially to standstill. Thereafter, the armature moves to the attracted position to short-circuit the "plugging" resistor and transfer control to the accelerating resistors which, as more fully described hereinafter, are short-circuited sequentially with predetermined intervening time delays.

Further objects and advantages of my invention will become apparent from the following description and for a better understanding reference should now be had to the accompanying drawings in which Fig. 1 is a diagrammatic representation of a control system embodying my invention in one form; Fig. 2 is a side view of the Winter electromagnetic switch preferably em-

ployed in obtaining the desired "plugging" and time limit acceleration control of the current limiting resistors in the motor armature circuit; and Fig. 3 is a diagrammatic representation of a control system embodying my invention in another form.

Referring to the drawings, the motor to be controlled is indicated as having an armature 10 and a series field 11, and this motor is arranged to be connected to a suitable direct current source of supply 12 including the supply lines L1 and L2 for operation in either direction by means of pairs of reversing or directional contactors Fa and Fb having the switches 13 and 14 for the forward direction of motor operation and the contactors Ra and Rb having the switches 15 and 16 for the reverse direction of motor operation. The current limiting means or protective resistance included in the motor armature circuit has a plurality of sections, a resistance section 17 being provided for controlling the "plugging" action and the resistance sections 18 and 19 being provided for accelerating purposes. Any number of resistance sections desired may be employed. The resistor 17 is controlled by means of a "plugging" contactor 20 having a normally open shunting switch 21 and a normally closed auxiliary switch 22, and the resistor sections 18 and 19 are respectively controlled by the accelerating contactors 23 and 26 provided with the normally open shunting switches 24 and 27 and the normally closed auxiliary switches 25 and 28. A line contactor 29 having a normally open main switch 30 and a normally open auxiliary switch 31 is provided for disconnecting the motor from the source of supply when a disconnecting switch 32 is open to de-energize the winding 33 of the contactor 29. In this manner, the source of supply 12 may be suitably energized and upon closure of the disconnect switch 32 the winding 33 is energized to close the main switch 30 of the motor circuit. Thereafter, the contactor 29 is sealed closed by closure of the auxiliary switch 31 until the supply 12 is de-energized.

Each of the contactors 20, 23 and 26 is provided respectively with the auxiliary or restraining windings r and the main or closing windings c whose effect on the operation of the contactors is more fully described here below. The restraining coil r of the contactor 20 is connected through the normally closed auxiliary switch 22 and across the terminals of the motor armature 10 and the reversing switches 13, 14, 15 and 16 so as to be energized responsively to the countervoltage of the motor. The normally closed switch 22 is operated to the open position, when the contactor 20 moves its normally open shunting switch 21 to the closed position which shunts or short-circuits the "plugging" resistor 17 to render it inactive. The closing coils c of the contactors 20, 23 and 26 are energized in a circuit which may be traced from line L1 through the disconnect switch 32 to a suitable manual controller, such as a drum controller 34. The drum controller 34 supplies the closing coil c of contactor 20 from line L1 through a conductor 35, the coil c and by the conductors 36 and 37 to line L2. The closing coils c of the contactors 23 and 26 are similarly supplied from line L1 through the drum controller 34, a conductor 38 and through the coils c and the conductors 36 and 37 to line L2. As shown, the drum controller 34 must be moved to its second forward or second reverse position designated respectively as F2 and R2 to energize coil c of the contactor 20. Similarly, the drum controller

must be moved to positions F3 and R3 to energize coils c of the contactors 23 and 26.

The restraining coils r of the accelerating contactors 23 and 26 are respectively connected in parallel with the preceding resistance sections 17 and 18 through the auxiliary contacts 25 and 28. In this manner, coil r of the contactor 23 is energized by the voltage drop across the "plugging" resistor 17, when the switch 21 is open, and is short-circuited by closure of the switch 21. Coil r of the contactor 26 is first connected across both of the resistance sections 18 and 19 so as to be energized by the voltage drop thereacross and is finally short-circuited upon closure of both of the switches 24 and 28.

The principle of operation of the several contactors 20, 23 and 26 will be best understood by referring to Fig. 2 wherein the preferred form of operating structure is illustrated. As shown, there is provided a pivoted armature 39 gravity biased clockwise to the normal position and carrying a suitable switching structure 40. This armature cooperates with a multi-legged frame 41 having a lower or closing leg C provided with the closing coil c and a restraining leg R provided with the restraining coil r. The upper right hand end of the armature 39 normally resides adjacent an extending portion 42 of the frame 41 which in effect forms a third leg for the frame. Thus two complete parallel flux paths are provided. The main flux path includes the legs C and R, the connecting portion of the frame 41 and the lower left hand end of the armature 39. The secondary flux path by which the armature 39 may be magnetically restrained in the normal position includes the upper part of the armature, the leg R and the portion 42 of the frame 41. Suitable shims of nonmagnetic material are provided at point 42 to adjust the reluctance of the secondary flux path.

With the foregoing understanding of the elements and their organization in this system the operation of the system itself will readily be understood from the following description:

Referring to Fig. 1, the system including the source of supply 12 is shown normally de-energized. By suitable means (not shown) the source 12 including the lines L1 and L2 may be energized. Thereafter closure of the disconnect switch 32 energizes the upper segment 43 of the master switch 34, thereby connecting the winding 33 of the line contactor 29 in a circuit traceable from line L1 and the segment 43 by conductor 44, the coil 33, and the conductors 36 and 37 to line L2. Operation of the contactor 29 closes the line switch 30 of the motor circuit and also closes the auxiliary switch 31 to complete a holding circuit for the winding 33. The drum controller is then moved from the "off" position shown to its first forward position F1, whereupon the forward control contactors Fa and Fb including the forward switches 13 and 14 are operated and the motor armature 10 and field winding 11 energized with all the resistance sections 17, 18 and 19 in the motor circuit. The windings of the forward contactors Fa and Fb are energized from a segment 45 of the drum controller 34 and through a conductor 46 and these windings to the conductors 36 and 37 and line L2. Simultaneously, an auxiliary switch 47 operated by contactor Fa is closed to energize the lower portion of the drum controller 34 in a circuit traceable from the segment 45 through the conductor 46, the switch 47, and a conductor 48 to a controller segment 49.

At this time the holding or restraining coil r of the "plugging" contactor 20 is short-circuited across the motor armature 18 and the forward switches 13 and 14 . Very little current flows through this coil r during normal starting conditions; that is, when the motor is started from rest because of the small voltage drop across the armature. When the drum controller is moved to its second forward position $F2$, the closing coil c of the "plugging" contactor 20 is energized from line $L1$ and a segment 58 of the master switch 34 through the conductor 35 , the coil c and the conductors 36 and 37 to line $L2$. If the motor is at standstill or is operating in its proper running direction, the contactor 20 quickly picks up to close the shunting switch 21 and short-circuits the "plugging" resistor 17 substantially without time delay.

Referring to Fig. 2 for purposes of illustration, in the "plugging" contactor 20 the winding r is so wound and connected as to assist the flux generated by the winding c to cause the armature 39 to pick up whenever the coil c is energized and the motor is at standstill or running in the normal direction. This is due to the fact that under these normal starting conditions coils r and c complement each other in causing flux to flow in the main flux path including the legs R and C of the frame 41 . As stated above, during normal starting very little current flows through coil r . However, coil r does constitute a short-circuited winding that tends to give the contactor 20 time delayed operation in moving the armature 39 to the attracted position by opposing the building up of flux in the leg R . Quick movement of the armature 39 to the attracted position during normal operating conditions of the motor is accomplished by increasing the reluctance of the secondary magnetic circuit by a suitable thickness of nonmagnetic shims at point 42 so that the "plugging" contactor 20 is substantially quick closing in spite of having a short-circuited winding r . Upon closing of the contactor 20 , its auxiliary contacts 22 open to break the circuit of the coil r and thereby enable the contactor 20 to drop out or return to the normal position quickly upon a subsequent deenergization of its closing coil c when the drum controller is moved to the "off" position or through the "off" position to a reverse position.

Before the closure of the shunting switch 21 by operation of the contactor 20 , the restraining coils r of the accelerating contactors 23 and 26 are energized, coil r of contactor 23 as a function of the voltage drop across the "plugging" resistor 17 and coil r of the contactor 26 as a function of the voltage drop across the "plugging" resistor 17 and accelerating resistor 18 . In each case the contactors 23 and 26 cannot pick up due to the fact that the holding force at point 42 of the secondary flux path of the contactors, shown in Fig. 2, aids the force of gravity in holding the armature 39 in the normal position. Thus it may be said that the contactors 23 and 26 are magnetically restrained or locked open in the normal position at this time. Also, the direction of energization or polarity of these restraining coils r of the accelerating contactors 23 and 26 is such that they oppose rather than assist the closing magnetization of the closing coils c to maintain the contactors 23 and 26 in the normal open position even when the closing coils c are energized. This is due to flux concentration at the holding gap 42 , the flux in the legs R and C of the magnetic frame 41 , shown in Fig. 2, moving in the

same direction in each leg. In this manner, the flux from the leg C is denied entrance into the leg R and through the main flux path and so is forced to pass across the gap 42 and join with the flux in the secondary magnetic path in magnetically restraining the armature 39 in its normal position shown.

Upon closure of the shunting switch 21 , if the drum controller 34 was previously moved to its third forward position $F3$ to energize the coils c of the contactors 23 and 26 , restraining coil r of the contactor 23 is short-circuited by closure of the switch 21 and the contactor 23 then operates to the attracted position after a substantial time delay. Time delay operation of the contactor 23 results once the restraining coil r of the contactor is short-circuited since the closing coil c is then the only coil energized. The coil c finally brings the flux in the leg R of the frame 41 to a zero value and then builds up flux in this leg in the reverse direction, all against the inductive delaying effects of the short-circuited coil r . Upon operation of the contactor 23 to the attracted position, shunting switch 24 closes to short-circuit the first accelerating resistance section 18 a predetermined time after the closure of the "plugging" contactor switch 21 . At the same time the auxiliary switch 25 of the contactor 23 is opened to break the short-circuit on the restraining coil r of this contactor and prepare the contactor for fast drop out or return to the normal position when the closing coil c is subsequently deenergized by moving the master switch 34 to the "off" or reverse positions.

After time delayed closure of the shunting switch 24 by the contactor 23 , obviously the first accelerating resistor 18 is rendered inactive by short-circuiting and the current in the motor circuit increased to accelerate the motor. At the same time coil r of the accelerating contactor 28 , which coil was first energized as a function of the voltage drop across the resistance sections 17 and 18 and then by the voltage drop across the resistance section 18 alone when the resistance section 17 was short-circuited, is itself short-circuited by the closure of the shunting switch 24 . Time delayed closure of the contactor 23 then occurs a predetermined time interval after the closure of the shunting switch 24 . This closes the shunting switch 27 to short-circuit the resistance section 19 and accelerate the motor to full speed.

The time delay operation of the contactor 26 is substantially identical to the time delay operation of the contactor 23 described above and is due to a flux reversal and inductive retardation of flux change in the leg R of the contactor 26 similar to that described in connection with the accelerating contactor 23 . When the second accelerating resistance section 19 is short-circuited by closure of the shunting switch 27 , the motor is accelerated to full speed, all of the control resistance being rendered inactive. Simultaneously with the closure of shunting switch 27 the auxiliary switch 28 opens to break the short-circuit on the coil r of the contactor 26 , thereby enabling the contactor 26 to drop out or return to its normal position quickly without substantial time delay when the master switch is moved to its "off" or reverse positions.

If the master switch 34 is not moved to its third forward position $F3$ until after the shunting switch 21 has been closed, the time delay operation of the contactor 23 is due only to the in-

ductive retarding effects of the short-circuited coil r of the contactor 23 in opposing the building up of flux in the leg R of the contactor. Thus the time delay in the latter case will be shorter than the time delay resulting if the master switch 34 was moved directly from its "off" position to its third position to energize the closing coil c of the contactor 23 before the shunting switch 21 was operated. Obviously, if the master switch is moved to its second position F2 and allowed to remain there until the motor has accelerated and increased its counter-voltage, it is unnecessary to delay the short-circuiting of the first accelerating resistor 18 for the longer time delay interval because the countervoltage of the motor assists in preventing the current in the motor circuit from exceeding a safe value. Even though contactor 23 operates with a shorter time delay, the contactor 26 will operate with its usual time delay since its operation is dependent upon the closure of the shunting switch 24. In this case, since the coils c of both the contactor 23 and the contactor 26 are energized simultaneously by moving the master switch 34 to its position F3, coil c of the contactor 26 will always be energized prior to the closure of shunting switch 24, and the time delay operation of contactor 26 will be due to a reversal of flux in leg R as previously described.

Assuming now that the motor is operating at full speed and that it is desired to "plug" the motor quickly to rest and then accelerate it in the opposite or reverse direction, this operation is accomplished by operating the master switch 34 in the reverse direction to its reverse positions R1, R2, and R3. The operator usually accomplishes this operation in a single complete movement, quickly throwing the master switch from the full speed forward position F3 to the full speed reverse position R3. As the master switch is moved from forward position F3 to forward position F2, the energizing circuits of the accelerating contactors 23 and 26 are interrupted and these contactors open their switches 24 and 27 to insert the resistance sections 18 and 19 into the motor circuit without any substantial time delay. As mentioned above, the contactors 20, 23, and 26 are all relatively fast on drop out because their auxiliary switches 22, 25, and 28 were opened with the operation of these contactors to the attracted position to break the short-circuits on the restraining coils r of each of the contactors. Movement of the master switch 34 from its position F2 to its position F1 causes the energizing circuit of the coil c of the "plugging" contactor 20 to be interrupted, as a result of which this contactor opens its switch 21 and inserts the "plugging" resistor 17 in the motor circuit. In a like manner, as the master switch 34 is moved to its central or "off" position, the energizing circuit for the forward contactors Fa and Fb is interrupted and these contactors open the forward switches 13 and 14 to disconnect the motor from the supply source. Also, the auxiliary switch 41 of the contactor Fa opens to de-energize the lower portion of the master switch 34.

In the first reverse position R1 of the master switch 34 an energizing circuit is completed for the operating coils of the reverse contactors Ra and Rb. This energizing circuit is readily traced from line L1 through the disconnect switch 32, the segments 43 and 51, a conductor 52, the coils of the contactors Ra and Rb, and through the conductors 36 and 37 to line L2. The contactors

Ra and Rb close their switches 15 and 16 in response to energization and connect the motor to the line for rotation in the reverse direction. An auxiliary switch 53 of the contactor Rb is also closed to energize segment 49 of the controller 34. It should here be noted that even though the direction of the current supply to the motor armature 10 has been reversed by opening the forward switches 13 and 14, and closing the reverse switches 15 and 16, the restraining coil r of the "plugging" contactor 20 is still connected across the terminals of the motor armature 10 from a point on line L1 to a point between the motor armature and its field winding 11. Thus the countervoltage of the motor causes the coil r of the contactor 20 to be energized in a direction to oppose the magnetic flux generated by the closing coil c. That is, the flux in the legs R and C of the contactor 20 flows in the same direction in each leg to concentrate a flow of flux through the holding gap 42.

By properly designing the reluctances of these magnetic circuits, the contactor 20 may be made to close when the motor reaches a predetermined low speed, preferably a speed approaching substantially standstill. At the predetermined low speed, due to the fall off of the counter-voltage of the motor, the closing coil energization is sufficient relative to the energization of the restraining coil to overcome the restraining flux at the gap 42 of the contactor and the force of gravity and the contactor closes to its attracted position. In this manner, by retaining the contactor 20 and its shunting switch 21 in the normal open position until the motor slows down to reduce its countervoltage sufficiently to permit operation of the contactor and the shunting switch 21 for short-circuiting the resistor 17, the motor is protected against the abnormal high currents that result during the "plugging" operation.

After closure of shunting switch 21, acceleration of the motor in the reverse direction is then had as previously described in connection with forward acceleration. If the master switch has been moved to reverse position R3 before the switch 21 closed, a substantial and long time delay will occur in the operation of the contactor 23 to close its shunting switch 24. On the other hand, if shunting switch 21 closes before the master switch is moved to position R3, a substantial but shorter time delay in the operation of the contactor 23 will result, contactor 26 in any case operating with the long flux reversing time delay. Finally, with the closure of all the shunting switches 21, 24, and 27, the motor is operated at full speed in the reverse direction.

Referring now to Fig. 3, similar elements are numbered similarly to the numbering in Figs. 1, the forward and reverse contactors, the supply, the motor circuit and the master switch circuits being substantially the same as those shown in Fig. 1. Fig. 3 differs from Fig. 1 in the manner in which the closing coils c and restraining coils r of the contactors 20, 23 and 26 are connected and energized. In the present instance, the coil r of the "plugging" contactor 20 is connected across the resistance section 17 and a portion of the resistance section 18 to a point X. This circuit may be traced from point X on the resistance section 18 through a conductor 60, the auxiliary switch 22, a conductor 61 to a midpoint between the series connected coils r and c, and from this midpoint through coil r , a conductor 62 and the conductor 36 joining the lower ends of the windings of the contactors Ra, Fb, Rb, and Fa and to the

conductor 37 which connects with resistor 17. The coil c of the contactor 20 is connected from line L1 and the master switch 34 by a conductor 64 through the coil c, the midpoint between the coil r and the coil c, the conductor 61, and through the auxiliary switch 22 and the conductor 68 to the point X on resistor 18. Coil c is also connected, as stated above, in series with coil r and through it and the conductors 62, 36, and 37 to line L2. Thus coils r and c are connecting in series circuit from line L1 to L2 while a separate circuit including the auxiliary switch 22 extends from a midpoint between the coils r and c to point X on resistor 18. When switch 22 is closed, coil c is energized as a function of the voltage drop across the motor armature 10, field winding 11 and resistances 19 and a portion of 18; and coil 5 as a function of the voltage drop across the other portion of resistance 18 and the resistance 17.

The restraining coil r of the contactor 23 is connected across the resistance section 17 to be energized responsively to the voltage drop thereacross in a circuit which may be traced from the conductor 37 connected at one side of the resistance section 17 through the conductors 36 and 62, the auxiliary switch 25, a conductor 65 to a midpoint between the series connected coils c and r, through the coil r to the other side of the resistance section 17. The restraining coil r of the contactor 26 is connected across both of the resistance sections 17 and 18 to be energized responsively to the voltage drop thereacross in a circuit which may be traced from the conductor 37 through the conductors 36 and 62, the auxiliary switch 28, a conductor 66 to a midpoint between the series connected coils r and c and through the coil r to a point between the resistance sections 18 and 19. The closing coils c of the contactors 23 and 26 are energized from line L1 and the lower portion of the master switch 34 through a conductor 67, the respective coils c, the respective conductors 65 and 66, the respective auxiliary switches 25 and 28, and by the conductors 62, 36, and 37 to line L2.

The description of operation of the control system illustrated in Fig. 3 proceeds from the time when the motor is energized with all the resistance sections 17, 18 and 19 inserted in the motor circuit. The initial steps to achieve this condition of operation are the same as described in connection with Fig. 1, the source of direct current supply 12 being suitably energized, the disconnect switch 32 closed to operate the line contactor 33 and close its switches 30 and 31, and the master switch 34 being moved from its "off" position shown to its first forward position F1 to energize the forward contactors F_a and F_b to close the forward switches 13 and 14 and the auxiliary switch 47.

At the time the motor is energized by closing the forward switches 13 and 14, the coil r of the contactor 20 is also energized, its polarity or direction of energization being complementary to that of the closing coil c as energized later under normal operating conditions when the master switch is moved to its second forward position F2. Coil r of the contactor 20, as previously stated, is connected across the resistance section 17 and a portion of the resistance section 18 so as to be energized responsively to the voltage drop across this resistance. Briefly, this circuit may be traced from point X on the resistor 18 through the elements 68, 22, 61, coil r, 67, and 36 to the conductor 37 which joins with 75

the resistor 17. Even though coil r is energized, it cannot by itself close the contactor 20 due to the magnetic force on the armature 39 at point 42, the flux generated by coil r flowing in the secondary flux path of the contactor. Movement of the master switch 34 to its position F2 energizes closing coil c of the contactor 20, and if the motor is at standstill or running forward when coil c is energized, the contactor 20 closes quickly substantially without time delay. This prompt operation of the contactor 20 to the attracted position is due to the complementary fluxes from the coils c and r which assist each other in causing flux to flow in the main flux path so that flux flows in opposite directions in the legs R and C of the contactor. The coil c of the contactor 20 is connected to line L1 through the auxiliary switch 22 to point X on resistor 18 and in effect is connected across the armature 10, the field 11, the resistance 19, and a portion of the resistance 18 to be energized by the voltage drop across the armature field, and this portion of the total resistance. Upon operation of the contactor 20, the auxiliary switch 22 opens to connect coil c solely in series with coil r and across the motor circuit from line L1 to line L2. In this manner, after operation of the contactor 20, full line voltage is applied to the coils c and r to increase the holding force on the contactor 30 in the attracted position and prepare the contactor for fast dropout.

The restraining coils r of the contactors 23 and 26 are connected through their respective normally closed auxiliary switches 25 and 28 for energization as a function of the respective voltage drops across the resistor 17 and the resistors 17 and 18. Both of these coils are energized in a direction that opposes and prevents the closure of the contactors when their closing coils c are energized. When the master switch 34 is moved to position F3 before the closure of the "plugging" contactor 20 and its shunting switch 21, the accelerating contactors 23 and 26 remain open since the restraining coils r of the contactors 23 generate fluxes that oppose the fluxes of the closing coils c to cause a concentration of flux at the point 42 of each contactor to magnetically restrain the armatures 39 of the contactors in the normal position. When shunting switch 21 is closed, the coil r of the contactor 23 is short-circuited and tends to maintain the opposing flux of the leg R and then resist the building up of flux in this leg. The closing coil c of the contactor 23 after a predetermined time delay overcomes the effects of the short-circuited coil r, reverses the polarity of the flux in leg R and closes the contactor 23 to accelerate the motor.

The auxiliary contacts 25 of contactor 23 are opened with the operation of the contactor to connect coil c and coil r of the contactor in series circuit across lines L1 and L2. This circuit may be traced from line L1 through the master switch 34, the conductor 67, the coils c and r and through the closed switches 21 and 38, and the conductor 37 to line L2. At this time both coil r and coil c of the contactor 23 are energized in a direction to complement each other in increasing the total number of ampere turns closing and holding the contactor 23 in the attracted position. Thus a strong closing and holding force is obtained without the need for additional turns of energizing winding on the contactor other than those already present in the coils r and c. At this time also, since the short-circuit previously on coil r has been interrupted by the

opening of the auxiliary switch 25, the contactor 23 is ready for fast drop out or quick return to its normal position when the master switch is moved to its "off" or reverse positions.

With coils *c* and *r* of the accelerating contactor 23 connected and energized as described above, coil *r* performs three important and useful functions. It acts first as a sequencing means by being energized responsive to the voltage drop across the preceding resistance section 17 and being short circuited through the switch 21 which short circuits the resistance 17. In this manner, closure of the contactor 23 is always in sequence after closure of the contactor 20. Second, coil *r* of the contactor 23 acts as a timing means to always delay the operation of the contactor for a predetermined time after the coil *r* is short circuited. Third, the coil *r* acts as a closing means to increase the closing and holding power of the contactor 23.

Immediately upon closure of the shunting switch 24 which short-circuits the first accelerating resistor 18, the coil *r* of the contactor 26 is short-circuited. Thus the closing coil *c* is enabled to overcome, after a predetermined time delay, the inductive effects of the short-circuited coil *r* and reverse the polarity of the flux in the leg *R*. The contactor 26 and its shunting switch 27 closes to short-circuit the second accelerating resistor 19 and bring the motor up to full speed. During the closing of the contactor 26, its auxiliary contact 28 opens to connect the coil *r* in series with the coil *c* across the lines L1 and L2. This series circuit may be traced from line L1 through the master switch 34 and the conductor 67, the coils *c* and *r*, the closed switches 24, 21 and 30 through the conductor 37 to line L2. In this manner the coils *c* and *r* are energized to complement each other and materially increase the magnetic forces closing and holding the contactor 26 in the closed position. Also, as in the case of the contactor 23, the contactor 26 is ready for fast drop out or quick return to its normal position upon subsequent de-energization of the coils *c* and *r*, since the auxiliary switch 28 has opened to interrupt the short-circuit on coil *r*.

If the contactor 20 and its shunting switch 21 close before the master switch 34 is moved to its position F3, the coil *r* of the contactor 23 is simply short-circuited and serves to give a shorter time delay interval after the closing coil *c* is energized before the contactor 23 closes. In this case, the closing coil *c* need only overcome the inductive effects of the short-circuited coil *r* on the building up of flux in the leg *R* of the contactor 23. In any case, contactor 26 operates with the same predetermined time interval after the closure of the shunting switch 24, due to the fact that its closing coil *c* is always energized before the shunting switch 24 closes.

When the motor is "plugged" or reversed by quickly moving the master switch from its forward position F3 to its reverse position R3, the contactors 20, 23 and 26 drop out quickly. At the same time reverse contactors Ra and Rb operate to close the reverse switches 15 and 16 and auxiliary switch 53 for reversing the energization on the motor armature 10. Thereafter, due to the counter E. M. F. of the relatively backward running motor, the voltage on the restraining coil *r* of the "plugging" contactor 26 increases over the usual standstill or forward running voltage condition because of the increased current in the motor circuit due to the addition of

the countervoltage and line voltage during the "plugging" operation. Increased current in the motor circuit causes an increased voltage drop across the resistor 17 and that portion of resistor 18 up to point X across which coil *r* is connected. The relatively higher energization of coil *r* increases the magnetic restraining force at point 42 of the contactor 26 so that the armature 38 is more strongly restrained in the normal position during the "plugging" operation than is the case during normal starting or running conditions. If the point X on resistor 18 is correctly chosen, the voltage on the closing coil *c* of the contactor 26 will decrease over its voltage during standstill or forward running conditions of the motor or even reverse its polarity, since the countervoltage of the motor comes into play. This will become apparent when it is understood that the closing coil *c* of the contactor 26 is connected across the motor from line L1 to point X or, stating it in another way, coil *c* is connected across the reversing switches 13, 14, 15, and 16, the motor armature 10, the field winding 11, the accelerating resistor 18, and a portion of the accelerating resistor 19 so as to be subjected both to the voltage drop across the resistor 18 and a portion of the resistor 18 as well as to the countervoltage of the armature 10. In this manner, by relatively increasing the energization of the coil *r* during "plugging" to increase the magnetic restraining force on the armature 38 at the point 42 and by relatively decreasing or reversing the energization of the closing coil *c* by the countervoltage applied to the coil *c*, the contactor 26 is maintained open until the motor drops to a predetermined low speed from which the motor may be safely accelerated in the reverse direction.

Thereafter, the contactor 26 operates to its attracted position and closes the shunting switch 21 of the resistance section 17. Operation takes place because as the motor speed decreases the countervoltage decreases and causes the energization of the closing coil *c* to increase and the energization of the coil *r* to decrease. With the closure of the shunting switch 21, time delayed operation of the contactor 23 is initiated and, after a predetermined time interval, shunting switch 24 closes to short-circuit accelerating resistance section 18 and accelerate the motor. Again, a predetermined time after closure of the shunting switch 24, the contactor 26 operates to close its shunting switch 27 which short-circuits the accelerating resistance section 19 to bring the motor to full speed. The time delayed operation of the accelerating contactors 23 and 26 for motor operation in the reverse direction is similar for all purposes to the operation described for acceleration in the forward direction of motor operation.

Adjustment of the time interval operation of the various contactors may be made by adjusting the thickness of nonmagnetic shims at the point 42, shown in Fig. 2. Alternatively, time adjustment may be provided for by increasing or decreasing the resistance of the restraining coils *r* of the contactors 20, 23 and 26, and my invention contemplates such adjustment.

Although in the preferred forms of my invention shown I employ the Winter type of electromagnetic contactor, it will be obvious to those skilled in the art that other types of plural winding contactors or plural winding relays for controlling the usual single winding contactors may be employed without departing from this invention.

tion, and therefore, I do not wish to be limited to the embodiments illustrated but contemplate by the appended claims to cover any modifications as fall within the true spirit and scope of my invention.

What I claim as new and desire to secure by Letters Patent of the United States, is:

1. A time interval motor control system comprising a plurality of resistor sections in the motor armature circuit, a plurality of switching means each including a shunting switch for shunting said resistor sections, electromagnetic time delay means for effecting operation of at least one of said shunting switches a predetermined time after another of said switching means has operated including a magnetic structure provided with an armature normally biased to one position and arranged to be attracted and moved against said bias to an attracted position but also arranged to be magnetically restrained in said normal position, means for magnetically energizing said magnetic structure including a main winding and an auxiliary winding, means for energizing said main winding and said auxiliary winding, said windings when simultaneously energized serving magnetically to restrain said armature in said normal position, and means controlled by operation of said other one of said switching means to control said auxiliary winding thereby enabling said main winding to overcome the magnetic effects of said auxiliary winding on said armature after a substantial time interval has elapsed and effect operation of said armature to said attracted position after a substantial time delay, thereby to effect substantial time delay operation of said one shunting switch by the interaction of magnetic effects of said energized main winding and said controlled auxiliary winding.

2. A time interval motor control system comprising a plurality of resistor sections in the motor armature circuit, a plurality of magnetically operated switching means each including a shunting switch for shunting said resistor sections, electromagnetic time delay means for effecting operation of at least one of said shunting switches a predetermined time after another of said magnetically operated switching means has operated including a magnetic structure provided with an armature normally biased to one position and arranged to be attracted and moved against said bias to an attracted position but also arranged to be magnetically restrained in said normal position, means for energizing said magnetic structure including a main winding and an auxiliary winding, means for energizing said main winding and said auxiliary winding, said windings when simultaneously energized serving magnetically to restrain said armature in said normal position, means controlled by operation of said other one of said switching means to control said auxiliary winding thereby enabling said main winding to overcome the magnetic effects of said auxiliary winding on said armature after a substantial time interval has elapsed and effect operation of said armature to said attracted position after a substantial time delay, thereby to effect substantial time delay, operation of said one shunting switch solely by the interaction of magnetic effects of said energized main winding and said controlled auxiliary winding, and means including an auxiliary switch operated responsive to the operation of said armature to said attracted position to control said auxiliary winding for enabling fast return operation of

75 said armature to said normal position when said winding is de-energized.

3. A time interval motor control system comprising a plurality of resistor sections in the motor armature circuit, a plurality of magnetically operated switching means each including a shunting switch for shunting said resistor sections, electromagnetic time delay means for effecting operation of at least one of said shunting switches a predetermined time after another of said magnetically operated switching means has operated including a magnetic structure provided with an armature normally biased to one position and arranged to be attracted and moved against said bias to an attracted position but also arranged to be magnetically restrained in said normal position, said magnetic structure having a main winding and an auxiliary winding, means for energizing said main winding and said auxiliary winding, said windings when simultaneously energized serving magnetically to restrain said armature in said normal position, means controlled by operation of said other one of said switching means to control said auxiliary winding thereby enabling said main winding to overcome the magnetic effects of said auxiliary winding on said armature after a substantial time interval has elapsed and effect operation of said armature to said attracted position after a substantial time delay, thereby to effect substantial time delay operation of said one shunting switch solely by the interaction of magnetic effects of said energized main winding and said controlled auxiliary winding, and means including an auxiliary switch operable by movement of said armature to said attracted position to connect said main winding and said auxiliary winding in series circuit whereby said windings generate a complementary magnetic flux for substantially increasing the attracting force on said armature to said attracted position.

4. A time interval motor control system comprising a plurality of resistor sections in the motor armature circuit, a plurality of magnetically operated switching means each including a shunting switch for shunting said resistor sections, electromagnetic time delay means for effecting operation of at least one of said shunting switches a predetermined time after another of said magnetically operated switching means has operated including a magnetic structure provided with an armature normally biased to one position and arranged to be attracted and moved against said bias to an attracted position but also arranged to be magnetically restrained in said normal position, said magnetic structure having a main winding and an auxiliary winding, means for energizing said main winding and said auxiliary winding, said windings when simultaneously energized serving magnetically to restrain said armature in said normal position, means controlled by operation of said other one of said switching means to control said auxiliary winding thereby enabling said main winding to overcome the magnetic effects of said auxiliary winding on said armature after a substantial time interval has elapsed and effect operation of said armature to said attracted position after a substantial time delay, thereby to effect substantial time delay operation of said one shunting switch solely by the interaction of magnetic effects of said energized main winding and said controlled auxiliary winding, and means including an auxiliary switch operable by movement of said armature to said attracted position to connect said main winding and said auxiliary wind-

ing in series circuit whereby said windings generate a complementary magnetic flux for substantially increasing the attracting force on said armature in said attracted position, said armature thereby quickly returning to said normal position without substantial time delay when said windings are de-energized.

5. A time interval motor control system comprising a plurality of resistor sections in the motor armature circuit, a plurality of shunting switches for shunting said resistor sections, electromagnetic time delay means for effecting operation of at least one of said shunting switches a predetermined time after another one of said switches has operated including a magnetic structure provided with a multi-legged frame and an armature normally biased to one position and arranged to be attracted and moved against said bias to an attracted position but also arranged to be magnetically restrained in said normal position, said magnetic structure having a main winding on one leg and an auxiliary winding on another leg, means for energizing said main winding and said auxiliary winding, said windings when both energized magnetically restraining said armature in said normal position, said auxiliary winding being short circuited by closure of said other switch whereupon said main winding overcomes the magnetic effects of said auxiliary winding in said other leg by gradually reducing the flux therein to a zero value and then building up flux of reverse polarity therein against the inductive effects of said short circuited auxiliary winding to effect operation of said armature to said attracted position after a substantial time delay, thereby to effect time delay operation of said one switch to shunt the respective one of said resistor sections after operation of said other switch.

6. A time interval motor control system comprising a plurality of resistor sections in the motor armature circuit, switches for shunting said resistor sections, electromagnetic time delay means for effecting operation of at least one of said switches a predetermined time after another of said switches has operated including a magnetic structure having a main winding and an auxiliary winding, means connecting said auxiliary winding for energization responsive to the voltage drop of the resistor section controlled by said other switch, means for energizing said main winding, said windings when both energized generating flux in said magnetic structure for preventing operation thereof and of said one switch, said auxiliary winding being short circuited by closure of said other switch whereupon said main winding is enabled to magnetize said magnetic structure to effect operation of said one switch for shunting the respective one of said resistor sections a substantial time interval after the operation of said other switch and due substantially solely to the interaction of the magnetic effects in said magnetic structure by said windings.

7. A time interval motor control system comprising a plurality of resistor sections in the motor armature circuit, switches for shunting said resistor sections, electromagnetic time delay means for effecting operation of at least one of said switches a predetermined time after another of said switches has operated including a magnetic structure having a main winding and an auxiliary winding, means connecting said auxiliary winding for energization responsive to the voltage drop of the resistor section controlled by said other switch, means for energizing said main

winding, said windings when both energized generating flux in said magnetic structure for preventing operation thereof and of said one switch, said auxiliary winding being short circuited by closure of said other switch whereupon said main winding is enabled to magnetize said magnetic structure to effect operation of said one switch for shunting the respective one of said resistor sections a substantial time interval after the operation of said other switch, and means including an auxiliary switch operable by said electromagnetic means for interrupting said short circuit on said auxiliary winding substantially simultaneously with the operation of said one shunting switch thereby to enable fast return operation of said electromagnetic means when said main winding is de-energized.

8. A time interval motor control system comprising a plurality of resistor sections in the motor armature circuit, switches for shunting said resistor sections, electromagnetic time delay means for effecting operation of at least one of said switches a predetermined time after another of said switches has operated including a magnetic structure having a main winding and an auxiliary winding, means connecting said auxiliary winding for energization responsive to the voltage drop of the resistor section controlled by said other switch, means for energizing said main winding, said windings when both energized generating flux in said magnetic structure for preventing operation thereof and of said one switch, said auxiliary winding being short circuited by closure of said other switch whereupon said main winding is enabled to magnetize said magnetic structure to effect operation of said one switch for shunting the respective one of said resistor sections a substantial time interval after the operation of said other switch, and means including an auxiliary switch operable by said electromagnetic means substantially simultaneously with the operation of said one shunting switch for interrupting said short circuit on said auxiliary winding and thereby connecting said auxiliary winding for energization in series circuit with said main winding whereby said windings generate a complementary magnetic flux for substantially increasing the holding force of said magnetic structure.

9. A reversing motor control system comprising reversing switch mechanism for the motor, a current limiting device in circuit with the motor, means including an electromagnetic structure having a multi-legged frame and an armature for controlling said current limiting device, energizing means for said electromagnetic structure including a pair of energizing windings on respective legs of said frame, means connecting one of said windings across the motor terminals so as to be energized responsive to the counter-voltage of the motor for magnetically restraining said armature in a predetermined position during "plugging" conditions of said motor, and means for energizing the other of said windings in a manner whereby during normal running operation of the motor said energizing means when energized causes substantially prompt operation of said armature to another position to render said current limiting device inactive, said windings interacting during "plugging" conditions of the motor to generate flux in said electromagnetic structure for magnetically restraining said armature from operating to said other position for rendering said current limiting de-

vice inactive until the motor speed is sufficiently reduced for safe forward operation in the opposite direction.

10. A reversing motor control system comprising reversing switch mechanism for the motor, a current limiting device including a plurality of resistance sections in circuit with said motor, means including an electromagnetic structure having a multi-legged frame and an armature and being provided with a pair of energizing windings for controlling at least a predetermined one of said resistance sections, means connecting one of said windings across the motor terminals and a portion of said current limiting device and in a manner so as to be energized responsive to the countervoltage of the motor, and means connecting the other of said windings across another portion of said current limiting device so as to be responsive to the voltage drop therein and in a manner whereby during normal running operation of the motor said windings cooperate when energized to operate said armature to a predetermined position for rendering said predetermined one of said resistance sections promptly inactive, said windings interacting during "plugging" conditions of the motor to generate flux in said electromagnetic structure for magnetically restraining said armature from rendering said last mentioned resistance section inactive due to a relative decrease or reversal of current flow in said one winding and a relative increase in current flow in said other winding during said "plugging" conditions until the motor speed is sufficiently reduced for safe operation in the opposite direction, said armature thereupon operating to said predetermined position for rendering said predetermined one of said resistance sections inactive.

11. A reversing motor control system comprising reversing switch mechanism for the motor, a current limiting device including a plurality of resistance sections in circuit with said motor, means including an electromagnetic structure having a multi-legged frame and an armature provided with a pair of energizing windings for controlling at least a predetermined one of said resistance sections, means connecting one of said windings across the motor terminals and a portion of said current limiting device and in a manner so as to be energized responsive to the countervoltage of the motor, means connecting the other of said windings across another portion of said current limiting device so as to be responsive to the voltage drop therein and in a manner whereby during normal running operation of the motor said windings cooperate when energized to operate said armature to a predetermined position for rendering said predetermined one of said resistance sections promptly inactive, said windings interacting during "plugging" conditions of the motor to generate flux in said electromagnetic structure for magnetically restraining said armature from rendering said last mentioned resistance section inactive due to a relative decrease or reversal of current flow in said one winding and a relative increase in current flow in said other winding during said "plugging" conditions until the motor speed is sufficiently reduced for safe operation in the opposite direction, said armature thereupon operating to said predetermined position for rendering said predetermined one of said resistance sections inactive, and means including an auxiliary switch controlled by said armature for connect-

ing said windings in series circuit when said armature is operated to said predetermined position for increasing the magnetic force holding said armature in said predetermined position.

12. A time interval motor control system comprising a plurality of accelerating resistors in the motor armature circuit, switches for shunting said resistors, electromagnetic time delay means for effecting operation of said switches sequentially after a preceding one has operated to shunt its resistor including a plurality of multi-legged magnetic structures each having an armature, a main winding and an auxiliary winding, means connecting each of said auxiliary windings across the preceding one of said resistors to be energized responsively to the voltage drop thereacross, means for energizing said main windings each in a direction to oppose the flux generated by said auxiliary windings in a portion of said frames, said windings when all energized generating fluxes in said frames that magnetically restrain said armatures in the normal position, said auxiliary windings being short circuited by the closure of the one of said switches controlling the preceding one of said resistors, and means for closing a first of said switches whereby the remaining switches operate in a definite succession each a substantial time interval after the operation of the preceding switch of the succession and due solely to a reversal of flux in said portions of said frames under the inductive effects of said short-circuited windings.

13. A reversing motor control system comprising a reversing switch mechanism, current-limiting means in the motor circuit, said current-limiting means having a "plugging" section and an accelerating section, means including a "plugging" switch for rendering said plugging section inactive during normal running operation of said motor and for maintaining said "plugging" section active during "plugging" conditions of the motor until the motor speed is sufficiently reduced for safe operation in the opposite direction, means including a switch for controlling said accelerating section of said current limiting means, electromagnetic time delay means for effecting operation of said switch a predetermined time after said "plugging" switch has operated to render said "plugging" section inactive including a magnetic structure provided with an armature normally biased to one position and arranged to be attracted and moved against said bias to an attracted position but also arranged to be magnetically restrained in the normal position, means for magnetically energizing said magnetic structure including a main winding and an auxiliary winding, means for energizing said main winding and said auxiliary winding, said windings when simultaneously energized serving magnetically to restrain said armature in said normal position, and means controlled by operation of said "plugging" switch to control said auxiliary winding, thereby enabling said main winding to overcome the magnetic effects of said auxiliary winding on said armature after a substantial time interval has elapsed and effect operation of said armature to said attracted position after a substantial time delay, thereby to effect substantial time delay operation of said accelerating switch by the interaction of magnetic effects of said energized main winding and said controlled auxiliary winding.
